UNITED STATES PATENT OFFICE.

GEORGE W. KING AND HARRY J. BARNHART, OF MARION, OHIO, ASSIGNORS
TO THE MARION STEAM SHOVEL COMPANY, OF SAME PLACE.

FRICITION-CLUTCH.

SPECIFICATION forming part of Letters Patent No. 666,348, dated January 22, 1901.

Application filed October 14, 1899. Serial No. 733,568. (No model.)

To all whom it may concern:

Be it known that we, GEORGE W. KING and HARRY J. BARNHART, residing at Marion, Marion county, Ohio, have invented certain new and useful Improvements in Friction-Clutches; and we do hereby declare the following to be a full, clear, and exact description of the invention, such as will enable others skilled in the art to which it pertains to make and use the same.

Our invention relates to improvements in strap-clutches.

The objects of our invention are, more particularly, to render a strap-clutch operative by steam under pressure upon the face of a piston within a cylinder carried by a rotary power-transmitting member which is operatively mounted upon the end portion of the shaft upon which is loosely mounted the drum or rotary member engageable by the strap of the clutch; to run the steam-supply pipe into the end and centrally of the shaft and a suitable distance longitudinally of the shaft and thence to the steam-pressure-receiving end of the cylinder; to form the bore in the shaft into which the said pipe extends larger diametrically than the pipe, so as to form an air-space around the pipe and accommodate the circulation of air through the pipe-containing portion of the shaft, and thereby avoid overheating of the said portion of the shaft; to conduct water resulting from condensation of steam leaking into the space behind the piston in the cylinder into the aforesaid bore and drain the same from the shaft at the steam-pipe-receiving end of the shaft, and thereby prevent the bespattering of the machinery by the said water, and to attain the results indicated—namely, the prevention of overheating the shaft and a satisfactory removal of any water resulting from the condensation of steam behind the piston of the cylinder by a construction that is simple, convenient, and inexpensive.

With these objects in view and to the end of realizing other advantages hereinafter appearing the invention consists in certain features of construction and combinations of parts hereinafter described, and pointed out in the claims.

In the accompanying drawings, Figure I is

a side elevation, mostly in section, of a friction-clutch and mechanism embodying our invention. Fig. II is an end elevation, partly in section. Fig. III on the sheet containing Fig. I is a sectional view in detail and shows certain parts on a scale larger than the corresponding parts are shown in Fig. I. Fig. IV is an elevation in detail, mostly in section, on line IV IV, Fig. I. Portions are broken away in the drawings to reduce the size of the same and to more clearly show certain features of construction.

Referring to the drawings, *a* designates a horizontally-arranged shaft, and *b* represents a drum that is loosely mounted upon the shaft and provided at one end with an external annular flange *b'*, that has the circumferentially-extending peripheral rim *b*², that is operatively engaged or disengaged by the friction-strap *c*, according as the said strap is tightened or loosened, as will hereinafter appear, upon the rim. A suitably - driven wheel *d*—a spur-gear in the case illustrated—employed in transmitting power to the rim *b*², is operatively mounted upon the shaft adjacent to the aforesaid flanged end of the drum. A short oscillating shaft *e* is supported from the wheel *d* near the latter's periphery, and the said shaft is arranged horizontally and parallel with the axis of the wheel. The shaft *e* is arranged a suitable distance from the external periphery of the rim *b*² and has an eccentrically-arranged and eccentric-forming pin *e'* formed upon the inner end of the shaft and overlapping the said rim. One end of the strap *c* is attached to the eccentric *e'*, whence the strap extends along and almost completely around the rim *b*², and has its other end attached to a pin *d'*, that is supported from the wheel *d* near the latter's periphery and near the shaft *e*. The shaft *e* at its opposite or outer end is operatively provided with a lever *e*², extending inwardly toward the central portion of the wheel *d* at one side of the wheel's hub. Normally the strap *c* is loose relative to the belt-embraced rim *b*²; but the oscillation of the shaft *e* by means of the lever *e*² and means, hereinafter described, employed for the operation of the said lever in the direction required to bring the eccentric *e'*, and conse-

quently the attached movable end of the strap, nearer the relatively stationary end of the strap will tighten the strap upon the rim b^2 , and thereby establish operative connection between the drum-rotating wheel d and the drum.

The means employed to operate the lever e^2 as required to render the strap c operative comprises a piston operated by fluid under pressure. The said piston has its head f' arranged within and movable endwise of a cylinder f , that is supported from the wheel d in any approved manner and is arranged, preferably, at a right angle or almost at a right angle to the lever e^2 and a suitable distance from the lever and between the periphery of the wheel and the wheel-hub's side that is opposite the hub's side at which the said lever is arranged. The rod f^2 of the piston extends through a stuffing-box f^3 , formed upon the inner end of the cylinder, and is operatively connected at its outer end by means of a link f^4 with the outer end of the lever e^2 . A spiral spring g is confined upon a rod g' , that is arranged parallel with the piston-rod. The rod g' has its inner end connected by a link g^4 to the lever e^2 , preferably at a point between the piston-rod and the shaft e . The spring g is inclosed, preferably, in a case f^5 , that is formed externally of the cylinder f and extends longitudinally of the cylinder. The outer end of the rod g' is screw-threaded, and the spring g is confined upon the rod between the inner end wall f^6 of the chamber of the case f^5 and a washer g^2 , interposed between the outer end of the spring and a nut g^3 , mounted upon the outer threaded end of the rod. Obviously, therefore, the spring g acts to retain the lever e^2 and the connected friction-strap in their normal and inoperative position, and the effect of fluid-pressure upon the larger piston face or area is the actuation of the piston and the connected lever e^2 in the direction required to render the friction-strap operative.

The means for conducting the fluid-pressure to the chamber of the cylinder comprises a port f^7 , formed in the surrounding wall of the said chamber at the cylinder's end that is opposite the larger area of the piston, which end is the outer end in the case illustrated. A pipe h communicates at one end with the port f^7 and has its opposite end portion extending through an aperture d^3 , formed laterally in the hub d^2 of the wheel d , into the inner end of a bore a' , formed centrally in and longitudinally of the clutch-bearing end portion of the drum-supporting shaft a , which bore extends to the outer extremity of the said end portion of the shaft. The pipe h at the inner end of the bore a' is connected by means of an elbow h' with a pipe h^2 , that extends centrally and longitudinally of the bore a' and beyond the bored end of the shaft and is in open relation with the eduction fluid-pressure-conducting port l^2 of a valve-chest l . Pipes h and h^2 turn together with the

wheel d , whereas the connection between the pipe h^2 and the valve-chest is stationary. The connection between the pipe h^2 and the port l^2 of the valve-chest comprises, preferably, a pipe h^3 , that communicates at one end with the said port and has its other end attached to one end of an elbow h^4 , whose other end forms a part of a stuffing-box h^5 , that embraces the connected end of the pipe h^2 . The pipe h^2 can freely turn within the stuffing-box, that prevents leakage of steam at the swivel-joint thus formed between the pipes h^2 and h^3 . The elbow has an external lug or projecting member h^6 arranged opposite the stuffing-box and having its outer end engaging a stationary object s , that prevents the pipe h^3 , and consequently the stuffing-box h^5 , from becoming displaced or disconnected from the pipe h^2 by steam-pressure within the elbow h^4 and the pipe h^2 .

The valve-chest l is supported in any approved manner. The chest has three ports, arranged the one l^3 centrally between the others l' and l^2 . The central port l^3 constitutes the exhaust-port of the chest and communicates with the exhaust-pipe l^4 . The port l^2 of the chest illustrated communicates, as already indicated, with the pipe h^3 . The pipes h^2 and h^3 constitute the fluid-pressure-supply pipe-line for the cylinder f , and the other outer port l' of the valve-chest establishes communication between the valve-containing chamber of the valve-chest and the pipe L , that constitutes the fluid-pressure-supply pipe for the valve-chest. A slide-valve o is suitably arranged and seated within the valve-chest and is provided in the usual manner with a cavity o' , that has the arrangement and size required to render it capable of establishing communication between the exhaust-port and the cylinder-connecting pipe-line in the exhausting and normal position of the valve. The valve o has its stem o^2 extending outside of the valve-chest to and a suitable distance below the operator's stand or platform p . A bell-crank lever r is arranged below the platform or stand p and is fulcrumed horizontally and transversely, as at r' , to a bracket p' , depending from and rigid with the platform p . The lever r in its normal position has one of its arms extending downwardly from the lever's axis and its other arm extending toward the valve-chest and operatively connected with the depending stem t of a pedal, whose head t is arranged a suitable distance above the platform p . The depending arm of the lever r is operatively connected by a link w with the outer end of the valve-stem. A stationary bracket k affords bearing for the said link, and the link is pivoted horizontally and transversely, as at w' , to the valve-stem. A collar w^2 is formed upon the link w near the pivot w' . The bearing-affording support h is arranged between the said collar and the bell-crank lever, and a spiral spring w^3 is mounted upon the link and confined between the said sup-

port k and the collar w^2 and acts to retain the valve in the latter's normal and exhausting position, wherein the clutch is idle. A spiral spring t^2 is mounted and confined upon the 5 pedal's stem t' between the pedal's head and the platform and acts to retain the pedal and the connected bell-crank lever in their normal position.

The operation of our improved clutch is as follows: The chamber of the chest l is in continuous communication with the fluid-pressure-supply pipe L . The valve o normally bridges or covers the exhaust-port b^3 and the eduction-port b^2 and establishes open relation 10 between the said ports. The depression of the pedal t tilts the bell-crank lever in the direction required to pull outwardly upon the valve-stem and shift the valve in the direction and to the extent required to uncover 15 the eduction-port b^2 , when fluid-pressure issues into pipe h^2 from the valve-chest's chamber and is conducted by means of the pipes h^2 and h and the cylinder-port f^7 into the chamber of the cylinder at the large area or 20 face of the cylinder's piston and results in the actuation of the piston and strap-connected mechanism as required to render the strap operative, and upon the release of the 25 pedal t the springs t^2 and w^2 return the pedal and the valve, respectively, into the normal position, and spring g returns the cylinder's piston to its normal or starting position and results in the exhausting of the cylinder, because in the normal position of parts the 30 fluid-pressure-receiving chamber of the cylinder is in open relation, by means of port f^7 , pipes h and h^2 , port b^2 , valve o , and port b^3 , with the exhaust-pipe.

As already indicated, the valve's stem o^2 40 and the connected valve are moved in the direction required to place the eduction-port b^2 of the valve-casing in open relation with the chamber of the said casing by the depression of the pedal t and upon the release of the 45 said pedal are returned into their normal position by the action of the spring w^2 .

Another feature of our invention consists in means provided for taking care of the drip or moisture that leaks into the cylinder's 50 chamber at the smaller face or area of the piston and avoid bespattering of the machinery with the drip. A pipe m communicates with the cylinder's chamber at the stuffing-box bearing end of the cylinder and is arranged 55 to conduct from the cylinder the drip or moisture accumulating in the cylinder's chamber at the smaller area or face of the piston. The said pipe connects at its opposite end with the lateral aperture d^3 , formed in the hub of 60 the wheel d . As already indicated, the aperture d^3 accommodates the extension of the pipe h to the center or axial line of the shaft a , where the said pipe is connected with the pipe h^2 , and the said aperture communicates 65 at its inner end with a lateral aperture a^2 , formed in the shaft and communicating with the inner end of the bore a' , that is formed

centrally and longitudinally of the shaft and accommodates the location of the pipe h^2 . The said bore is diametrically larger than the pipe h^2 to render it capable of adequately accommodating and conducting any water or moisture accumulating within the said bore to the bore's outer end. The bore's outer end is enlarged diametrically, as at a^3 , to receive the 70 inner end of a bushing n flush with the surrounding wall of the bore. The said enlarged outer end of the bore has its surrounding wall screw-threaded and engaged by corresponding threads formed upon and externally 75 of the inner end of the bushing. The bushing rotates, therefore, with the shaft. The bushing has its outer end reduced diametrically, as at n' , to render it capable of snugly but easily embracing the pipe h^2 . A chambered collar i is loosely mounted upon the bushing at the outer end of the shaft and between the shaft's end and a flange n^2 , formed upon and externally of the outer end portion 80 of the bushing. The chamber of the said collar is placed in open relation with the chamber of the bushing by means of a series of apertures n^3 , formed laterally in the collar-bearing portion of the bushing at suitable 85 intervals circumferentially of the bushing, and consequently the chamber of the collar is in open relation with the bore a' of the shaft, so that any water or moisture accumulating 90 within the said bore can escape through the said perforations into the collar and thence 95 into the drain-pipe i' , that is secured to the collar in any approved manner and communicates with the collar's chamber.

The pipe h^2 and the bushing n are preferably secured together by a set-screw u , that extends into engagement with the pipe through a correspondingly lateral threaded hole in the outer end portion of the bushing. The pipe h^2 is secured, therefore, to the shaft, so that there is no liability of the said pipe unscrewing from the elbow h' , that, as already indicated, connects the said pipe h^2 with the pipe h .

Steam-pressure is preferably employed, and obviously there would be leakage of steam past the piston within the cylinder f —that is, steam would leak from the pressure-receiving face of the piston to and between the piston and the surrounding wall of the cylinder's chamber into the said chamber behind the piston, and the steam thus leaking into the space behind the piston would, if allowed its own course, condense and drip out at the piston-rod bearing end of the cylinder, and this drip on account of the cylinder revolving with the wheel d would be thrown off by centrifugal force in every direction. This spattering of condensed steam would be a source of annoyance, especially in freezing weather. By the provision of the stuffing-box f^3 around the piston-rod and the cylinder's drain-pipe m connected with the bore a' of the shaft the drip or condensed steam forming within the cylinder behind the pis-

ton is caused to pass to the end of the shaft, where the centrifugal force is not sufficient to throw it off; but the drip is drained at the end of the shaft and causes no inconvenience.

- 5 By the use of the bushing n and the collar i and a connected pipe the drip can be carried to any point entirely out of the way. We would remark also that when the spring g forces the piston back air is sucked into pipe m , and 10 consequently into the bore a' of the shaft. This ingress of air into the shaft cools the latter, and consequently cools the box j , that affords bearing for the shaft at the outer end of the hub of the wheel d and formed upon 15 the stationary framework j' . If steam-pressure were employed, pipe h^2 would be hot and heat would radiate to the shaft, and the circulation of air around the said pipe within the shaft will prevent overheating of the shaft.

20 What we claim is—

1. The combination, with a shaft, a rotary power-transmitting member operatively mounted upon the shaft, another rotary member loosely mounted adjacent to the 25 power-transmitting member, a clutch for establishing operative connection between the said rotary parts, a fluid-pressure cylinder carried by one of the said rotary parts and instrumental in rendering the clutch operative, the piston within the cylinder, means 30 acting to retain the said piston in its inoperative position, and a bearing j for the shaft, of a bore formed centrally in and extending longitudinally of the shaft, a steam-supply pipe arranged centrally and longitudinally of 35 and diametrically smaller than the said bore and in open relation with the fluid-pressure-receiving chamber of the cylinder, a passage-

way establishing open relation between the said bore and the cylinder's chamber behind 40 the piston, substantially as and for the purpose set forth.

2. The combination, with a shaft, a rotary power-transmitting member operatively mounted upon an end portion of the shaft, 45 another rotary member loosely mounted adjacent to the power-transmitting member, a clutch for establishing operative connection between the said rotary parts, and a fluid-pressure cylinder carried by one of the said 50 rotary parts and instrumental in rendering the clutch operative, of a bore formed centrally in and extending longitudinally of the shaft to the outer extremity of the aforesaid shaft, a steam-supply pipe arranged centrally and longitudinally of and diametrically 55 smaller than the said bore and in open relation with the fluid-pressure-receiving chamber of the cylinder, a passage-way establishing open relation between the said bore and the cylinder's chamber behind the piston, 60 the cylinder's chamber behind the piston, bushing secured to the shaft and snugly embracing the aforesaid pipe, which bushing has its chamber communicating with the aforesaid bore and is provided with discharge-aper- 65 tures, and a chambered collar mounted upon the bushing and having an outlet, substantially as and for the purpose set forth.

Signed by us at Marion, Ohio, this 22d day of September, 1899.
